UNITED STATES PATENT OFFICE.

DANIEL L. BATES, OF DAYTON, OHIO, ASSIGNOR OF ONE-HALF TO BENJAMIN F. ARNOLD, OF SAME PLACE.

WASHING-MACHINE.

SPECIFICATION forming part of Letters Patent No. 331,675, dated December 1, 1885.

Application filed July 17, 1885. Serial No. 171,859. (No model.)

To all whom it may concern:

Be it known that I, DANIEL L. BATES, a citizen of the United States, residing at the city of Dayton, county of Montgomery, and State of Ohio, have invented certain new and useful Improvements in Agitator Washing-Machines; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in that class of washing-machines in which an agitator-head, with stick-coupling device to receive and hold the ends of the wooden rods or sticks, is employed, and suitable gearing for operating it.

The object of my invention is to provide means for securely holding the wooden rods in the sockets shown, so that there will be little liability of their working loose and dropping out. This object I attain by the construction substantially as shown in the drawings, and hereinafter described and claimed.

Similar letters refer to similar parts in the accompanying drawings.

Figure 1 represents a vertical section of my invention in connection with a suitable gearing and tub. Fig. 2 represents a perspective view of my agitator-head and stick-coupling. Fig. 3 represents a bottom view of the agitator-head and coupling. Fig. 4 represents a perspective view of the washer-head detached.

A represents an ordinary suds-tub, provided with legs, lid, &c. To the cover B is secured a suitable frame, C, of any desired form or construction, for supporting the usual driving gear-wheel, E, provided with a handle, D, for operating it, the teeth of said gear-wheel meshing with those of a pinion, F, upon the upper end of a vertical shaft, G, whereby the shaft may have motion imparted to it as required.

The gearing, also the frame, as above described, may be variously modified or changed in their form or construction, as they form no part of my invention, and I hereby desire to be understood as not confining myself to the precise means shown.

To shaft G is pinioned a skeleton or agitator head, H, provided with semicircular sockets S S S S, extending outwardly in direction from dotted lines M N in Fig. 1, to receive wooden rods K K. Beneath said skeleton head is received on shaft G a loose washer, I, provided with like semicircular sockets, S' S' S' S', to lock and hold wooden pins K K K. The semicircular sockets S S S S and those in washer I form together circular sockets to receive the wooden rods. Upon the lower end of shaft G are threads to receive nut J, by means of which and washer I, pressing in the direction of dotted lines M N, the wooden rods K K K are firmly held at an outward inclination or allowed to drop out at the will of the operator.

Having fully described my invention, what I desire to secure by Letters Patent is—

1. The combination, with the shaft, operated substantially as described, of an agitator-head having semicircular sockets, agitator-sticks, a washer below said head and provided with corresponding semicircular sockets, and a nut for adjusting the washer toward the head, to lock the sticks between them, as set forth.

2. The combination, with the shaft, operated substantially as described, of an agitator-head, the sticks, the subjacent adjustable washer, and the nut on the shaft, the said head and washer being constructed, substantially as shown, to clamp the sticks between their peripheral surfaces and incline them outward, as set forth.

DANIEL L. BATES.
